UNITED STATES PATENT OFFICE.

GEORGE R. CORNWALL, OF RYE, NEW YORK, ASSIGNOR, BY MESNE ASSIGNMENTS, TO
JAMES G. COFFIN, TRUSTEE.

PROCESS OF PRODUCING PRINTING-TYPES.

1,128,267.

Specification of Letters Patent.

Patented Feb. 9, 1915.

Application filed April 17, 1905, Serial No. 256,124. Renewed July 18, 1914. Serial No. 851,817.

To all whom it may concern:

Be it known that I, GEORGE R. CORNWALL, a citizen of the United States, residing at Rye, in the county of Westchester and State of New York, have invented new and useful Improvements in Processes of Producing Printing-Types, of which the following is a specification.

An object of the invention is to provide 10 a process for producing integral printing types having a planographic printing surface; also to provide thereby a type which is of great durability and which is capable of yielding impressions of great clearness 15 and artistic value.

These and other objects of the invention will more fully appear from the following description.

The invention consists in the novel im- 20 provements, steps and processes herein shown and described.

The accompanying drawings, referred to herein and forming a part hereof, illustrate certain steps in the process, or processes of 25 my invention, the same serving in connection with the description herein, to explain the principles of the invention. The drawings are somewhat diagrammatic in character and do not necessarily represent the relative 30 proportions of objects nor of the parts of objects, drawings of this nature being best adapted to illustrate inventions of this character.

Of the drawings: Figure 1 indicates type 35 blanks of various unit widths; Fig. 2 shows completed types the surfaces having been rolled in ink to show the characters thereon; Fig. 3 represents a body of assembled type blanks at one step in the process; Fig. 4 40 illustrates a form of holding means for a body of assembled blanks; and Fig. 5 depicts a method of registering a character-bearing negative or positive with the surfaces of the blanks.

45 Printing types of this character have many properties differing from those of integral types heretofore known and are adaptable to uses to which the types now known in the art are not adaptable. One 50 of the uses to which they are so adaptable is for the purpose of taking or yielding an impression which is capable, under proper treatment, to give a planographic printing

surface. A particular instance of this use is where a number of such types are assembled 55 manually, or by machine, to form a justified line unit, and are then impressed upon a planographic line bar in a transferable medium. The adaptability of said line units, composed of integral types of this na- 60 ture to easy and accurate justification and correction, substitutions, etc., will be readily understood. Types of this character possess many other advantages and are susceptible to many other uses. 65

In the process of producing types of this character blanks are provided with surfaces of such unit widths as correspond to the relative unit widths of the characters to be placed upon the different blanks. It is common to assign a unit width value of two to the letter "i," of four to the letter "a," and of six to the letter "w," etc. These blanks may be of any suitable material, such as wood, rubber, metal, glass, etc., and may be 70 of any suitable height, and where found convenient, they may be of the same height as ordinary relief types. While, so far as certain features of this invention are concerned, the types may be produced or manufactured individually, other features of the invention contemplate the production of 75 said types in quantities, and a process forming part of this invention is described for the production of the said types in quanti- 80 ties. 85

Blanks 1 of suitable material and corresponding in unit widths to the character or characters to be placed thereon are assembled together, as illustrated at Fig. 3. Holding means for said blanks are provided in the carrying out of the process and such holding means is herein shown as a frame or chase 2 having pressure-exerting means 3 exerting an adjustable pressure against 90 members or rules 4 which are shown in contact with the sides of the assembled blanks 1. The adjustable pressure-exerting mem- 95 bers 3 may be screw-threaded into the chase 2, and the regulation of the pressure secured 100 by the rotation of the said members 3 by suitable turning means 5. Upon the surface of the said blanks, either before being assembled or afterward, but preferably after they are assembled, a coating of a light-sen- 105 sitive material, such as sensitive asphalt,

chromated albumen, or chromated gelatin, or other suitable substance, is spread, and may be allowed to dry thereon.

A negative or positive bearing the characters which it is desired to impress upon the sensitive surface of the blanks, is prepared having the characters thereon of proper size and in proper relation so as to permit of the characters being correctly registered or located with respect to the surface of the blanks. A convenient way of making such a negative is by producing a model design or character in a transferable medium. This design or character may then be laid down from said model upon a suitable sheet or surface as many times and in such relation or relations as may be desired or necessary. A negative may then be made from the sheet or surface, the production of the negative being regulated so as to secure the characters of proper size. A positive may be made by contact, or otherwise, from the negative when suitable or convenient. The negative 6 may be placed in contact with the sensitized surfaces 7 of the blanks and may be brought into accurate register with the said surfaces so that the characters carried by the negative may be symmetrically placed with respect to the said surfaces. This registration may be effected by registering means, such as 8, which may be affixed to the chase 2 and may be constructed to afford accurate regulation of the movement of the negative 6 in all directions. When the negative is properly placed it may be held by suitable clamping means 9, if desired, and the negative with the sensitive surfaces underneath is well exposed to the light. The negative is then removed and also the registering and clamping members 9 may be made movable, if desired. The surfaces of the said types, when the coating consists of chromated albumen or chromated gelatin may then be "developed" whereby the portions unaffected by the light are desensitized. By suitable treatment the parts not acted upon by the light may be dissolved to a greater or less degree, thus furnishing a planographic surface in very slight relief.

Substances admirably adapted for providing the surfaces for the blanks are the light-sensitive hydrocarbons. A well-known substance of this class is sensitive asphalt, mentioned above, which may be obtained in a well-known manner from commercial asphalt. The treatment of these substances is generally similar to that hereinbefore mentioned. The body of the types, as hereinbefore indicated, may be metal, glass or other suitable material. The asphalt is flowed over the surfaces of the blanks and is allowed to dry and forms a sensitive layer or film thereon. It is then subjected to the action of light under the negative or posi-

tive and after such exposure is "developed" with turpentine, which is active toward the unexposed portions of the hydrocarbon film but is inert toward the exposed portions. The properties of the said hydrocarbons 70 are such that they produce a surface of great hardness and durability and adapted to give a practically unlimited number of impressions of great sharpness and clearness. The surfaces of the types, after such 75 treatment, will be found to have the portions acted on by the light capable of taking ink and rejecting moisture, while the portions which were not acted on by the light through the negative will be ink-rejectant and moisture-taking. These types are then adaptable 80 for printing by the planographic method, i. e., upon the surfaces being first dampened and then inked the designs or characters alone will take the ink and upon 85 impression will yield the design or character in the ink to a proper receiving surface.

From all the foregoing it will be understood that among other results an integral type has been provided having a surface 90 adapted for planographic printing; that said surface possesses printing qualities of a high character and that it possesses great durability; that a method has been provided for producing such types easily and inexpensively.

The invention, in its broader aspects, is not limited to the particular means employed in, or manner of carrying out the process, nor to any particular means, manner or embodiments, as many changes may be made therein without departing from the main principles of the invention and without sacrificing its chief advantages.

While the type blanks and type characters 105 have been described herein as conforming to the "unit system", it will be understood that this is not essential to the invention so far as regards certain of its features, but the use of the unit system is contemplated 110 by the invention in other of its aspects. It is only essential, so far as regards the first-mentioned features of the invention, that each of the blanks be formed in a width bearing a proper relation to the width 115 of the character which it is to receive, whether they are composed on a unit system or not. It will be understood also that the blanks will be formed of a face-height which is convenient and appropriate for the kind 120 of letter to be impressed thereon.

What I do claim as my invention and desire to secure by Letters Patent, is:

1. The process of producing printing types which consists in assembling a plurality of 125 blanks of suitable width, each of said blanks having a sensitized surface, and projecting upon the surface of each blank a character by means of the action of light.

2. The process of producing printing types 130

which consists in assembling a plurality of suitable blanks of a width corresponding to the width of the character desired, holding said blanks in their assembled position 5 so that their faces may lie in a single plane, applying a sensitized coating to the said surfaces, and projecting characters thereon by the action of light.

3. The process of producing printing types 10 which consists in assembling a plurality of suitable blanks, holding said blanks in their assembled position so that their faces may lie in a single plane, applying a sensitized coating to the said surfaces, bringing a negative 15 containing a plurality of character images into register with said assembled blanks so that an image in the negative will be properly positioned with respect to the surface of each blank, and subjecting the said 20 surfaces to the action of light through said negative.

4. The process of producing printing types which consists in assembling a plurality of blanks so that their surfaces will lie substantially in a single plane, holding same in fixed relation when assembled, applying a sensitive coating or layer to the surfaces of said blanks, placing a negative containing a multiplicity of character images in contact 25 with said surfaces, bringing said negative into accurate register so that a character image in the negative will be properly positioned with respect to the surface of each of the blanks, exposing said surfaces to the action 30 of light passing through the said negative, and then developing said surfaces.

5. The process of producing printing types which consists in assembling a plurality of blanks of proper unit width so that their 40 surfaces will lie substantially in a single plane, holding same in fixed relation when assembled, applying a sensitive coating or layer to the surfaces of said blanks, placing a negative containing a multiplicity of character images in contact with said surfaces, bringing said negative into accurate register 45 so that a character image in the negative will be properly positioned with respect to the surface of each of the blanks, exposing said

surfaces to the action of light passing 50 through the said negative, and then developing said surfaces.

6. The process of producing printing types which consists in assembling a plurality of blanks so that their surfaces will lie substantially 55 in a single plane, holding same in fixed relation when assembled, applying a sensitive coating or layer to the surfaces of said blanks, drying said coating or layer, placing a negative containing a multiplicity 60 of character images in contact with said surfaces, bringing said negative into accurate register so that a character image in the negative will be properly positioned with respect to the surface of each of the blanks, exposing said surfaces to the action of light 65 passing through the said negative, and then developing said surfaces.

7. The process of producing printing types which consists in assembling a plurality of 70 blanks, holding same in fixed relation when assembled, applying a coating of sensitive asphalt to the said surfaces, drying said coating, placing a character-bearing negative in proper register with the said surfaces so that a character will be impressed 75 upon each of said surfaces, exposing the said surfaces to the light through the negative, then developing said surfaces.

8. The process of producing printing types 80 which consists in assembling a plurality of blanks, holding same in fixed relation when assembled, applying a coating of sensitive asphalt to the said surfaces, drying said coating, placing a character-bearing negative 85 in proper register with the said surfaces so that a character will be impressed upon each of said surfaces, exposing the said surfaces to the light through the negative, then developing said surfaces with turpentine. 90

In testimony whereof I have signed my name to this specification in the presence of two subscribing witnesses.

GEORGE R. CORNWALL.
